CLAIM

The ornamental design for a hat attachable flashlight holder, as shown and described.

DESCRIPTION

FIG. 1 is a perspective view of a hat attachable flashlight holder showing our novel design;

FIG. 2 is a right side view thereof;

FIG. 3 is a rear side view thereof which is symmetric with the front side plan view;

FIG. 4 is a left side view thereof;

FIG. 5 is a top side plan view thereof; and,

FIG. 6 is a bottom plan view thereof which is symmetric.
